UNITED STATES PATENT OFFICE.

CARL BIERNAT, OF GLASFORD, ILLINOIS.

RAILWAY TIE AND RAIL FASTENER.

Application filed December 24, 1926. Serial No. 156,868.

This invention relates to improvements in rail fastenings for railroad ties, and it is the principal object of my invention to provide a rail fastening with which the use of the customary spikes, nails, etc., is entirely and positively dispensed with by providing a rail support which by the weight of the rolling stock will firmly hold the rails on the ties.

Another object of the invention is the provision of a rail fastening with which the foot flanges of the rails rest on the lower arms of pawls or the like fulcrumed intermediate their ends in the ties, the upper arms of which are adapted to be firmly pressed against the rail web at opposite sides thereof.

A further object of the invention is the provision of a rail fastening in which means are provided to hold one of the pawls rigidly in its upright position, while the other oppositely disposed pawl may readily be turned about its fulcrum, so as to allow a quick exchange of the rails, whereby means are provided for locking also this pawl into its rail web engaging position.

A still further object of the invention is to provide a railroad tie provided with means for facilitating the sliding of the rails into their seat upon the pawl arms.

These and other objects and advantages of my invention will become more fully apparent as the description thereof proceeds, and will then be more definitely pointed out in the appended claims.

In the accompanying drawings forming a material part of this disclosure:

Fig. 1 shows a railroad tie and rail fastening constructed according to my invention in vertical longitudinal section on line 1—1 of Figure 2.

Fig. 2 is a top plan view thereof.

Fig. 3 is a cross-section on line 3—3 of Figure 1.

Fig. 4 is a side elevation of a form of my invention in which means are provided for facilitating the sliding of the rails in place on the fastening.

Fig. 5 is a top plan view thereof.

As illustrated in Figures 1 to 3, of the drawings, a railway tie 10 of any well known construction and material, for instance as shown, has formed therewith at the rail supporting places, preferably at the rail joints as illustrated, where two rails 11 and 12 join and are secured together by the well known fish plates 13 and bolts 14, depre-

sions 15, 16 in which two pawls, in each depression, designated 17 and 18 of the form illustrated are fulcrumed intermediate their ends on pins 19 and 20 respectively, resting in the side walls of the depressions by their ends. Each of said pawls has a lower, shorter arm 21 and an upper longer arm 22.

The upper part of the longer arm of pawl 17 is formed as shown at 23, and is adapted to engage the web 24 of a rail below the head 25' thereof, while the upper part of the pawl 18 is formed as shown with a web engaging flat intermediary part or face 25 adapted to engage the web of the rail oppositely to finger 23 in the manner illustrated in Figure 1 between the rail head 25' and the foot flange 26 of the rail.

The rail foot flanges rest on top of the upper edges of the shorter or lower arms 21 of the pawls ending in two inner oppositely disposed flanges 27, 28.

While the pawl 17 is kept in its upright rail web engaging position almost stationary in the manner as for instance illustrated in Figure 4, the pawl 18 can be freely turned about its fulcrum pin to allow a sliding of the rail in its place on the fastening, it may also be locked in this position by the arrangement of a suitable stop pin 29 or the like.

The pivot pins 19, 20 have outer heads 30, and near their inner ends shallow recesses are formed within the tie below the axis of said pins, which are designated 31 and in which locking pins 32, 33 are resting placed in position before the rails are placed on the tie. Lugs or pintles 34 on the pawls 17, 18 extend into suitable sockets in the tie. The ties have anchors 35 and a central web 36 for embedding the same into the road bed material, while drainage channels 37 are provided to drain the water, etc., collecting in the depressions of the tie.

As illustrated in Figures 4 and 5, a wedge-shaped body 38 provided with downward extending pins 39 adapted to engage holes 40 in the body of the tie, may be arranged so as to facilitate the sliding of the rails onto the fastening.

The operation of my improved rail fastening will be entirely clear from the above description; after the pawls have been placed in the recesses or depressions of the ties and fulcrumed on their pins 19, 20 which have been locked in position by the

key-pins 32, 33, the rail is brought into position with its foot flange resting upon the shorter arms of the pawls and will be firmly held in this position by the pressure exerted by the rolling stock and the weight of the rails upon the lower arms of the pawls which, turning about their fulcrums, will have their upper arms firmly pressed into engagement with the rail webs on opposite sides thereof. It will be clear that while pawl 17 is held stationary, pawl 18 can be locked after adjustment of the parts by means of pin 29. The wedge 38 will facilitate the placing of the rails on the lower arm of pawl 17 whereafter pawl 18 is placed into position, to engage the rail. It is to be understood that such changes as come within the scope of the appended claims may be made without departure from the spirit of my invention.

Having thus described my invention what I claim as new and desire to secure by Letters Patent is:

1. A rail fastening comprising in combination with a railway tie having a depression in its body, a pair of pawls fulcrumed intermediate their ends, pins in said tie forming the fulcrums of said pawls, heads at the ends of said pins, and locking means for said pins at the part of the tie opposite to said heads, said pawls having lower shorter arms supporting the rail foot flange, and longer, upper arms adapted to engage the rail web at opposite points for securely holding the rail on said tie when the said shorter arms are depressed under the weight of the rails and the rolling stock, pressing said upper arms into engagement with said rail web, and means for locking

the parts in their adjusted rail holding position.

2. In a rail fastening of the class described, the combination of a railroad tie having depressions in its body, and a pair of pawls in said depressions fulcrumed intermediate their ends on pins in said depressions having lower, shorter arms flanged at their inner oppositely disposed ends to form supports for the rail foot flange, and upper longer arms adapted to firmly engage the rail webs between foot and head of the rail on opposite sides thereof for securely holding said longer arms in engagement with said rail and the rail in place upon the exertion of pressure upon the lower arms by the weight of the rails and rolling stock upon the same, and a means for locking said pins.

3. A rail fastening comprising in combination with a railway tie having a depression in its body, a pair of pawls fulcrumed intermediate their ends, means in said tie forming the fulcrums of said pawls, locking means for said fulcrum forming means, lower, rail foot flange supporting means on said pawls, and upper, rail web engaging means on said pawls, said lower supporting means for the rail foot flanges adapted to be depressed under the weight of the rails and the rolling stock thereon for firmly pressing the upper web engaging means against the rail web on opposite sides of the rail, and a stop pin for locking the parts in their adjusted rail holding position.

Signed at Glasford, in the county of Peoria and State of Illinois, this 27th day of November, A. D. 1926.

CARL BIERNAT.
